UNITED STATES PATENT OFFICE.

EMILE MERTZ, OF BASLE, SWITZERLAND.

APPARATUS FOR MOISTENING AIR.

SPECIFICATION forming part of Letters Patent No. 470,693, dated March 15, 1892.

Application filed July 29, 1891. Serial No. 401,087. (No model.) Patented in France September 11, 1888, No. 192,906; in Belgium September 17, 1888, No. 83,288; in Switzerland November 15, 1888, No. 54, and October 13, 1890, No. 2,745; in Italy December 6, 1888, LVII, 252, and in England January 23, 1891, No. 1,268.

To all whom it may concern:

Be it known that I, EMILE MERTZ, a citizen of France, residing at Basle, Switzerland, have invented certain new and useful Improvements in Apparatus for Moistening Air, of which the following is a specification, and which has been patented in France by patent of addition, dated October 13, 1890, and January 22, 1891, to Patent No. 192,906, dated 5 September 11, 1888; in Switzerland by Patent No. 2,745, dated October 13, 1890, and by patent of addition No. 77, dated January 28, 1891, to Swiss Patent No. 54, dated November 15, 1888; in Italy by patent of addition, dated 10 March 28, 1891, Vol. 25, 28,987, Vol. 42, 252, to patent dated December 6, 1888; to English Patent No. 1,268, dated January 23, 1891; Belgium patent of improvement, dated January 28, 1891, to Patent No. 83,288, dated September 15 20 17, 1888.

The present invention relates particularly to means for cleansing the water-atomizing valves of apparatus for moistening air.

According to this invention I connect the 25 atomizing-surfaces, against which the streams of water impinge as they issue from the nozzles, to a movable rod, so that by a change in the position of this rod the atomizing-surfaces are made to press upon the projecting 30 points of the plugs of the nozzles (which plugs are provided with capillary channels) and press the plugs back in their cases, and the channels of the plugs are in consequence automatically cleansed by the water which issues 35 from the valve under pressure.

In order to enable this invention to be fully understood, I will describe how it can be carried into practice by reference to the accompanying drawings, in which—

40 Figure 1 is a vertical axial section of an air-moistening apparatus constructed according to the preferred form of my invention. Fig. 2 is a horizontal section thereof cut immediately below the beaters F in Fig. 1. Fig. 45 3 is a vertical mid-section of a construction of the apparatus adapted to receive its supply of air from outside the apartment in which it is located. Fig. 4 is a horizontal section thereof taken in a plane just below the 50 beater F. Fig. 5 is a fragmentary vertical

section showing a modified form of atomizing-surface. Fig. 6 is a fragmentary plan view of the modification shown in Fig. 5. Fig. 7 is a detached view showing in elevation another modified form of atomizing-surface. Fig. 8 is a fragmentary plan view of the modified form of spraying-surface and its carrier shown in Fig. 7. Fig. 9 is a detached view showing one of the spraying-nozzles on a large scale in vertical axial section. Fig. 10 is a plan view of the nozzle shown in Fig. 9. Fig. 11 is a side elevation of the plug of the nozzle shown in Fig. 9, and Fig. 12 is a cross-section of the plug shown in Fig. 11.

Referring to Figs. 1 and 2, let A represent the well-known filter; B B, the nozzles, which consist of sockets e and movable plugs f, one of said parts being grooved; C C, the atomizing-surfaces; H, the carrier therefor; L, a plate or ring connected to the carrier H; E, the 65 usual fan; F, the usual beater-bars, and D the well-known turbine for driving the fan and beater-bars. G is an inclosing case of usual construction. The nozzles B may be of any well-known construction, and consist, essentially, of a socket and movable plug there-in, one of said parts having discharge-grooves, and said plug normally restricting the flow through the nozzle, but constructed when displaced to permit an increased flow in order 70 that the water rushing through the nozzle may cleanse its discharge-grooves.

In the construction shown in Figs. 9 to 11 the socket e is cylindrical and has a slightly-coned seat, and the plug f is inclosed in the 75 socket and has a conical portion normally engaging the coned seat of the latter, being in other respects movably located in the socket and adapted to be displaced inwardly thereof to open the nozzle. To permit this displacement, the plug is formed with a projecting point d at its outer end, which extends above the shell e and against which the atomizing disks or surfaces C abut to open the nozzle, as will be described hereinafter. In this construction the plug f is provided with small capillary outlets or grooves g and with larger tapering grooves h, and an annular groove i is turned out near the top of the plug and a larger annular recess j is provided at the lower 80 85 90 95 100

end of the groove *h*. The grooves *h* and *g* serve as passages for the water as it is discharged from the nozzle, as heretofore, while any impurities in the water which are held 5 back by these grooves will collect in the groove *i* and the recess *j* during the normal operation of the nozzle. When the nozzle is to be cleaned, it is only necessary to displace the plug *f*, whereupon the flow through the nozzles 10 will be increased to such an extent that it will wash out the accumulated impurities in the groove *i*, recess *j*, and the grooves *g* and *h*. When the cleansing operation is completed, the plug *f* upon being released resumes 15 its normal position and the nozzle throws out the ordinary jet of spray. This principle of construction and operation is well known.

In the apparatus shown in Figs. 1 and 2 the water, purified by the filter *A*, is driven 20 under pressure out of the nozzle *B* from below upward against the disks *C*, which have their surface arranged in steps, and in this way the water is converted into a condition of extremely fine division. The water under 25 pressure also drives a turbine *D*, which is arranged under the nozzle *B*, and upon the shaft of which a fan *E* and a cross-piece *F* are fixed. The fan *E*, as well as the cross-piece *F* and the atomizing-disks *C*, is placed within a casing 30 *G*, open above and below, so that by the rotation of the fan *E*, which revolves with the turbine *D*, a current of air is made to pass through the apparatus from below upward, and as the result of the contact of this current of air with the finely-divided water the 35 air takes up moisture and passes through the annular opening *a* of the casing *G* of the cylinder into the apartment which is to be moistened or cooled, as the case may be. The cross- 40 piece *F*, which rotates with the ventilator, serves to drive off laterally onto the casing *G* the drops of water which find their way onto the upper surface of the disk *C*, and thus prevent their passage through the fan *E*. The 45 number of atomizing-disks *C* is equal to that of the nozzles *B*, and these graduated disks *C* are attached to a common carrier *H*, which corresponds in form with the annular arrangement of the nozzles. The carrier *H* is secured 50 by means of screws *c* to two lateral projections *b* of a nut *K*, which is supported by the vertical screw *I*. To the said projections of the nut *K* are also attached the ends of a nearly-circular plate *L*, and the latter is in 55 addition connected with an arm *d* of the disk-carrier *H*, so that the position of the plate *L* and that of the disk-carrier *H* may be changed with that of the nut *K*. The spindle of the screw *I* is led at one end through one of the 60 arms *M M' M''* (which are cast in one piece with the casing of the turbine and which connect the latter with the cylindrical casing *G*) and at the other end through the arm *N* of the exit for the waste water of the turbine. At the 65 end of the spindle of the screw *I* is attached a handle or a ring *P*, and a spring *Q*, which rests below upon the arm *N* and is in contact

above with a socket *R*, fixed to the spindle *I*, presses the spindle *I* constantly upward. The atomizing disks or surfaces *C* are constructed when moved toward the valves *B* to engage the projecting ends *d'* of the nozzle-plugs *f* and displace the latter. Thus when the nozzles *B* are to be cleaned it is only necessary to draw down the screw-spindle *I* by 70 means of the ring *P*, so that the spindle with the nut *K* and the atomizing-disks *C* move downward together until the disks *C* press upon the points *d'* of the plugs and drive the latter back into their casings, so that then 80 the water which streams out of the nozzles under pressure can carry off with it the impurities which adhere to the plugs. As soon as the pull upon the spindle *I* ceases the latter, with the disks *C*, are brought back into 85 their normal position by means of the spring *G*, which has been previously compressed by the drawing down of the spindle *I*. The ring or plate *L* is constructed to move toward and surround the nozzle *B* when the surfaces *C* 90 operate to open the latter in order that the discharge from the nozzles may be intercepted, and thus be prevented from escaping below the casing *G*. The ring *L* has two recesses *l*, so that when the spindle *I* is drawn down the 95 arms *M M'* may not interfere with the movement of the ring *L*. The ring or plate *L* is further provided with a slot *m*, so that when the spindle *I* is drawn down the ring *L* may not strike against the inlet *S* of the water-supply. By means of this ring *L*, which slides upon the inner surface of the cylindrical casing *G*, the movement of the atomizing-disks *C* in any direction but a vertical one, when traction is made upon the spindle 100 *I*, is prevented. In addition to this, the ring *L* also serves to prevent the water from being thrown into the room when the nozzles are being cleansed—that is to say, when traction is made upon the ring *P* of the spindle *I*. A 110 revolving disk *k* is further attached to the spindle *I*, so that the screw *I* can be turned by hand, and by this rotation the nut *K*, which is united with the atomizing-disks *C* can, together with the latter, have its position altered more or less, so that the atomizing-disks *C* are made to approach or recede 115 from the nozzles, by which means the air as it streams through the apparatus is moistened in a correspondingly greater or less degree. 120

In the apparatus shown in Figs. 3 and 4 the casing *G* is secured to hollow bracket *P'*, screwed to a well, which, by means of openings capable of regulation, is in connection with the outer air as well as with the air of 125 the apartment, so that a mixture of the outer fresh air and of the unpurified air of the apartment can be moistened in the apparatus. The fan *E* then takes up the air which is to be moistened from the hollow bracket 130 *P'* and forces it after it has been moistened through the round opening *a'* into the atmosphere of the apartment. The opening *n*, by means of which the hollow bracket *P'* com-

municates with the outer air, is provided with a movable slide *o*, while the lateral openings *p*, by means of which the hollow bracket *P'* communicates with the air of the apartment, can be regulated by the slide *q*. The slides *q* are provided with buttons for the purpose of altering their position, and when the position of the slides is changed the slides *q* are guided by plugs which slide in slots *t*, arranged between the openings *p* of the side walls of the bracket *P'*.

As in the apparatus shown in Figs. 1 and 2, the water under pressure flows first through the filter *A* before it reaches the turbine *D* and the nozzles *B*. The axis of the turbine *D* also carries a cross-piece *F* and a fan *E*, and between the cross-piece *F* and the nozzles *B* are atomizing-disks *C* with graduated surfaces attached to a common carrier *H*. The latter is also connected with a nut *K*, supported by a screw *I*, and a ring *L* is attached to the nut *K* and also to the arm *d* of the disk-carrier *H*. The screw-spindle *I* is guided by a lateral projection *M* of the casing of the turbine, and by the arm *N* connected with the outflow-pipe of the waste water, and a spring *Q*, kept in position at one end by the arm *N* and at the other by a ring *R'* in the spindle *I*, presses the said spindle constantly upward. By pulling the ring *P* of the chain which is connected to the spindle *I* the disks *C* are, as in the apparatus shown in Figs. 1 and 2, made to approach the nozzles until they rest upon the points *d'* of the plugs and press the latter back into the sockets, so that the plugs of the nozzles are automatically cleansed by the water which streams out under pressure. By turning the spindle *I* the atomizing-disks *C* can also be shifted nearer to or farther from the valves in order to more or less moisten the air which flows through the apparatus. The guiding-ring *L* of the disks *C* is also provided with slots *u*, so that the lugs *v* of the hollow bracket *P'*, by means of which the casing *G* is secured by screws *x* to the bearer *P'*, do not interfere with the change of position of the ring *L*. The ring *L* has also a slot *m* to avoid any thrust upon the inlet-pipe *S* of the water-supply by the ring *L*. A cap *y* is fitted to the spindle *I* for the purpose of diverting the drops of water which fall upon it, so that no water may run along the spindle and escape from the apparatus. In both these apparatuses for the moistening of air lubricating-oil is placed in a reservoir *U*, (which surrounds the pivots of the common spindle or axis of the turbine *D*, the cross-piece *F*, and the fan *E*,) whence it can be drawn off through a tube *z*, attached to it and provided with cocks, and new oil poured into the reservoir *U* by means of a tube *V*.

Instead of several atomizing-disks *C*, as shown in Figs. 1 to 4, a single atomizing-ring *C'*, with graduated surface and attached to the carrier *H*, as shown in Figs. 5 and 6, might be employed for several valves. The atom-

izing-surfaces might also consist of obliquely-placed vanes or wings *C''*, attached to a common carrier *H*, as shown in Figs. 7 and 8.

It will be understood that I do not limit myself to the particular construction and arrangement of the apparatus as hereinbefore described and shown in the drawings, as this may be variously modified without departing from my invention.

Any suitable mechanical equivalent for the means shown for moving the atomizing-surfaces against the nozzles may be employed, as will be apparent to those skilled in the art, and the other details of construction may be modified as circumstances or experience may dictate without departing from the essential features of my invention.

What I claim is the following-defined novel features and combinations, substantially as hereinbefore set forth, namely:

1. In an apparatus for moistening air, the nozzle for discharging a jet of spray, said nozzle consisting of a socket and a movable plug, one of said parts constructed with discharge-grooves, and said plug normally restricting the flow through the nozzle, in combination with an atomizing-surface normally located before said nozzle and against which the spray is thrown, said surface being movable against said plug and constructed when so moved to displace said plug, whereby the flow through the nozzle is increased, and thereby its discharge-grooves are cleaned.

2. In an apparatus for moistening air, the nozzle for discharging a jet of spray, said nozzle consisting of a socket and a movable plug, one of said parts constructed with discharge-grooves and said plug normally restricting the flow through the nozzle, in combination with an atomizing-surface against which the spray is thrown, movable toward said nozzle and constructed when so moved to displace said plug, whereby the flow through the nozzle is increased and its discharge-grooves are thereby cleaned, and a plate or ring connected to said surface to move therewith and constructed when said surface is moved toward said nozzle to surround the latter and intercept the discharge therefrom.

3. In an apparatus for moistening air, the nozzle for discharging a jet of spray, said nozzle consisting of a socket and a movable plug, one of said parts constructed with discharge-grooves and said plug normally restricting the flow through the nozzle, in combination with an atomizing-surface against which the spray is thrown, constructed to be movable against said plug to displace said plug, whereby the flow through the nozzle may be increased, a movable carrier for said surface, and a spring tending to maintain said carrier in its normal position, whereby when said carrier and surface are moved toward said plug said spring is compressed and when said carrier is released it is restored by said spring to its normal position.

4. In an apparatus for moistening air, the

- nozzles B for discharging a jet of spray, movable plugs in said nozzles, atomizing-surfaces C, against which the spray is thrown, carrier H for said surfaces, plate or ring L, connected 5 to said carrier, and casing G, inclosing said surfaces, said surfaces, carrier, and plate constructed to be movable toward said nozzles until said surfaces abut against and displace said plugs for increasing the flow through the 10 nozzles, and said plate constructed when so moved to inclose said nozzles below said casing G and intercept the discharge therefrom.
5. In an apparatus for moistening air, the combination, with the nozzles B, having movable plugs, and the atomizing-surfaces C, the latter constructed to move against the plugs of said nozzles for opening them, of the carrier H for said surfaces, the rod I, connected to said carrier for operating the latter, and spring 15 Q, engaging said rod and tending to maintain the latter and said carrier and surfaces in their normal position, substantially as and for the purpose set forth.
- 20

6. In an apparatus for moistening air, the combination, with the nozzles B, having movable plugs, of the atomizing-surfaces C, constructed to move against the plugs of said nozzles for opening them, the carrier H for said surfaces, a plate or ring L, constructed to move with said surfaces, the casing G, the 25 nut K, to which said carrier and plate or ring are connected, and the rod I, adjustably connected to said nut for moving it and said plate, carrier, and surfaces toward said nozzles, said plate or ring having recesses to permit its 30 said movement, all combined and arranged substantially as and for the purpose set forth.

In witness whereof I have hereunto signed my name in the presence of two subscribing witnesses.

EMILE MERTZ.
